UNITED STATES PATENT OFFICE.

WILLIAM R. FARRELL, JR., OF NEW YORK, N. Y.

COMBINED DOOR KNOB AND BELL.

SPECIFICATION forming part of Letters Patent No. 721,945, dated March 3, 1903.

Application filed December 31, 1901. Serial No. 87,888. (No model.)

To all whom it may concern:

Be it known that I, WILLIAM R. FARRELL, Jr., a citizen of the United States, and a resident of New York city, State of New York, have invented certain new and useful Improvements in a Combined Door Knob and Bell, of which the following is a specification.

My invention relates to a new and useful combined door knob and bell, and is designed to produce a construction which will be simple, cheap, and effective.

In the following, with reference to the accompanying drawings, I have described a structure embodying my invention, the features thereof being more particularly pointed out hereinafter in the claims.

Figure 1 is a plan view of a door-knob embodying my invention in place on a door, portions being cut away to show the construction. Fig. 2 is a horizontal view, partly in section, along the line A B of Fig. 3, which is on a slightly-enlarged scale. Fig. 3 is a vertical sectional view along the line C D of Fig. 2. Fig. 4 is a horizontal sectional view along the line E F of Fig. 3. Fig. 5 is a horizontal sectional view along the line G H of Fig. 3. Fig. 6 is an elevation of certain disconnecting mechanism on an enlarged scale to show the construction and mode of operation more clearly.

Similar numerals indicate similar parts throughout the several views.

1 represents a portion of a door, showing the usual lock-case having the spring-latch 2.

3 represents the usual door-knob, secured to the end of spindle 4, which is of the usual construction and adapted to operate the latch 2.

5 is the base of the other door-knob, which is provided with a shell or bell 6, secured to the end of spindle 4, the bell 6 being adapted to turn with and operate said spindle in the same manner as knob 3.

7 is a sleeve having a circular periphery and mounted on spindle 4 inside of the bell-knob.

8 is a collar mounted on sleeve 7 and having a toothed wheel 9 preferably integral therewith.

10 is a plate fastened to base 5 by means of lugs 11 11 11 and supporting a spring-controlled pawl 12, adapted to hold wheel 9 against reverse movement.

13 is a collar on spindle 4, adapted to turn

therewith and having an arm 14, bearing a spring-controlled pawl 15, adapted to operate wheel 9.

16 is a pin on plate 10, adapted to raise the pawl 15 from the teeth of wheel 9 on a reverse movement of the collar 13.

17 is a spring-box having an extended periphery 18, provided with V-shaped cut-out portions 19, said spring-box bearing also a cog-wheel 20, adapted to coact with the spur-gear 21 on shaft 22, having its bearings in plate 10 and in a projection 23 from base 5. Shaft 22 bears at its upper end wheel 24, adapted to operate the bell-knocker 25, as shown in Fig. 4. Shaft 22 is provided with buttons 26 26, having rounded tops, as shown, and adapted to hold the end of lever 27 between them. Button 28 at the lower end of the shaft limits the upward movement of the same. Spring-controlled lever 27 is adapted to push shaft 22 upward and wheels 21 and 24 out of contact with wheel 20 and bell-knocker 25, respectively. The lever 27 projects through an aperture in base 5 and is cut away at 29 in such manner that when the lever is raised the cut-away portion may be pressed into a narrow portion of said aperture and hold the lever up.

30 is a spring adapted to be fastened at one end to collar 8 and at the other to spring-box 17. Collar 8 is provided with arms 31 31, having fingers 32 32, fitting over a spring 33, fastened to plate 10.

The operation of my device is as follows: The lever 27 being in extended position, as shown in full lines in Fig. 6, so that the wheels 21 and 24 are in contact with wheel 20 and bell-knocker 25, the knob 3 is rotated anticlockwise, causing the pawl 15 to turn the wheel 9, and consequently to wind spring 30 around the collar 8. In the initiatory movement the knob should not be turned so far as to unlatch the door, as by several partial rotations the spring is wound up sufficient to provide a storage of power. The spring 30 having been thus wound up sufficiently, the door is opened in the usual fashion by rotating the knob, and as the latch is released the fingers 32 32 release spring 33, permitting the spring-box to turn the wheel 20, actuating-gear 21 and causing the bell to ring. Should it be desired to disconnect the bell-ring,

mechanism, the lever 27 may be pushed up and into the position shown by dotted lines in Fig. 6, the rounded tops of buttons 26 26 permitting lateral movement of the same, in 5 which case the spring-box will move as before, but the bell mechanism will not operate. The duration of the ringing may be graduated by the number of cut-out portions in the periphery 18 of the spring-box, it being possible either that the bell may ring continuously as long as the spring will operate or that it may ring intermittently, as desired. In the illustration the bell is adapted to ring 15 four times to one revolution of the spring-box. Upon releasing the door-knob from the hand of the operator the latch-spring will cause the spindle to resume its initial position, the pawl 15 moving back over the teeth of wheel 9, which wheel is held from any backward movement by pawl 12. Should the person opening the door turn the knob in the wrong direction—that is, clockwise—the pin 16 will lift the pawl 15, so that it will not pass over the teeth of wheel 9, although the bell 25 mechanism will be released as before, and upon releasing the knob the latch-spring will cause the parts to take their initial positions and be ready for further operation. A spring 34 is adapted to hold the pawl 15 against the 30 teeth of wheel 9 when the same is in operation.

The proportions are so arranged that a partial winding of the spring will cause the spring-box to rotate sufficiently to ring the bell as 35 desired.

It is obvious that the form, proportions, and details of construction of the parts may be varied without departing from the spirit of my invention, and therefore I do not restrict 40 myself to the details shown; but

What I claim, and desire to secure by Letters Patent of the United States, is—

1. In a device of the class described, the combination of a spindle, two knobs mounted 45 thereon one of said knobs serving as a bell, a box surrounding said spindle and having an extended periphery said periphery having cuts or recesses therein, a spring connected to said spindle and to said box, a stop engaging 50 said cuts or recesses, a striker, mechanism intermediate said box and striker to actuate the

latter, means to move said stop out of engagement with said box to permit the spring to act to cause a series of successive blows of the striker.

2. In a device of the character described, the combination of a spindle, two knobs mounted thereon one of which serves as a bell, striker mechanism, a spring to actuate said mechanism secured to said spindle and means to wind said spring on giving the outer knob a partial rotation in one direction.

3. In a device of the character described, the combination of a spindle, two knobs mounted thereon one of which serves as a bell, a box surrounding the spindle having an extended periphery with cuts or recesses therein, a toothed wheel mounted on said box, a spring secured to said spindle and box, a second spring attached to said spindle and adapted to engage said cuts or recesses, a striker and mechanism intermediate the same and said box to cause the bell to ring when said second spring is released from engagement with said box.

4. In a device of the class described, the combination of a spindle, two knobs mounted thereon one of which serves as a bell, a toothed wheel mounted to rotate on said spindle, means to rotate said wheel, a striker-actuating mechanism, a shaft, a pinion mounted on said shaft and engaging said toothed wheel and a wheel also on said shaft adapted to operate the striker, and means to throw said pinion and wheel out of engagement respectively with said toothed wheel and striker.

5. In a device of the class described, the combination of a spindle, two knobs mounted thereon one of which serves as a bell, a bell ringing mechanism comprising a spring secured to said spindle and means to wind said spring upon a partial rotation of the spindle in one direction and means to render the winding mechanism inoperative if the spindle is turned fully in the opposite direction.

In witness whereof I have hereunto signed my name in the presence of two subscribing witnesses.

WILLIAM R. FARRELL, JR.
